US00D998390S

(12) **United States Design Patent** (10) **Patent No.:** **US D998,390 S**
(45) **Date of Patent:** **** Sep. 12, 2023**

(54) **KNOCK-DOWN DUMP BIN**

(71) Applicant: **Walmart Apollo, LLC**, Bentonville, AR (US)

(72) Inventor: **Alexander Micheal Alvarado**, Bentonville, AR (US)

(73) Assignee: **Walmart Apollo, LLC**, Bentonville, AR (US)

(**) Term: **15 Years**

(21) Appl. No.: **29/786,492**

(22) Filed: **Jun. 1, 2021**

(51) LOC (14) Cl. **06-04**

(52) U.S. Cl.

USPC **D6/675.2**; D6/675.1

(58) **Field of Classification Search**

(57) **CLAIM**

The ornamental design for a knock-down dump bin, as shown and described.

DESCRIPTION

FIG. 1 is a perspective view of a knock-down dump bin; FIG. 2 is a front view thereof; FIG. 3 is a back view thereof; FIG. 4 is a left view thereof; FIG. 5 is a right view thereof; FIG. 6 is a top view thereof; FIG. 7 is a bottom view thereof; FIG. 8 is a perspective view thereof with the left and right sides in a folded position; and, FIG. 9 is a perspective view thereof in an assembled embodiment with other knock-down dump bins. The broken lines represent portions of the knock-down bin and form no part of the claimed design. The broken lines represent environment and form no part of the claimed design.

1 Claim, 8 Drawing Sheets
